DESIGN FOR A DRESS

Gladys K. Cloyes, Houston, Tex.

Application November 24, 1939, Serial No. 88,454

Term of patent 7 years

To all whom it may concern:

Be it known that I, Gladys K. Cloyes, a citizen of the United States, residing at Houston, in the county of Harris and State of Texas, have invented a new, original, and ornamental Design for a Dress, of which the following is a specification, reference being had to the accompanying drawing, forming part thereof.

In the drawing:

Fig. 1 is a front elevation of a dress showing my new design.

Fig. 2 is a rear elevation of the same dress.

I claim:

The ornamental design for a dress, substantially as shown.

GLADYS K. CLOYES.
